UNITED STATES PATENT OFFICE.

WILLIAM F. CAPITAIN, OF CHICAGO, ILLINOIS, ASSIGNOR TO MARBER,
LUSE & CO., OF SAME PLACE.

DESIGN FOR TYPE.

SPECIFICATION forming part of Design No. 16,122, dated June 2, 1885.

Application filed March 28, 1885. Term of patent 3½ years.

To all whom it may concern:

Be it known that I, WILLIAM F. CAPITAIN, a citizen of the United States of America, residing at Chicago, in the county of Cook and State 5 of Illinois, have invented a certain new and original Design for a Font of Printing-Type, of which the following is a specification, reference being had therein to the accompanying printed specimens.

10 My invention consists of a new design for a font of printing-type, as hereinafter fully set forth, and as shown in the printed specimens.

The letters, characters, and numerals, and all their ceriphs of the design are formed of 15 lines of uniform thickness.

The right line of A extends below the bottom of the left line, and these lines do not meet, but are connected at the top by a horizontal line extended beyond the side lines. The middle line of this letter and of H extends across 20 and beyond the left side line.

The lower curve of B extends below and terminates in an upward curve near the back, above the bottom of the vertical line of the 25 letter.

The upper right portions of C, G, and S are formed by horizontal and downward vertical lines, and the bodies of these letters are formed by the continuation of the horizontal lines, 30 curved and terminating in C in a central scroll, and in G in a backwardly-extended horizontal line, and in S in a scroll.

The bottom horizontal line of E extends farther forward than the top line, and this bottom line of this letter and of L terminates in 35 an upward left oblique line.

The middle portions of E and F are formed by straight horizontal lines and forwardly-inclined lines. The right vertical lines of one 40 form of H and N and of the letter U and the upper inclined lines of K, X, and Y are extended above the left portions of those letters.

The upper ceriphs of J, K, and Y are extended farther beyond the left than the right 45 of the upper portions of these letters.

The left vertical line of M extends above and below the top and bottom of the left line, and the middle lines cross each other, and are connected at the bottom by a horizontal line.

50 The left vertical lines of both forms of N ex-

tend below the bottom of the right portions of the letter.

O and the body of Q are true circles. The distinguishing-mark of Q is a straight line inclined backward at the top, and extending an 55 equal distance above and below the bottom line of the body of the letter.

The line forming the upper forward portion of P is extended downward and connected with the vertical line near its base. 60

The upper forward portion of R is formed by a horizontal and curved line terminating in front of the middle of the vertical line, and the lower forward portion of this letter is formed by a straight line extended from the 65 termination of the upper portion downward obliquely to the right, below the bottom of the vertical line, and terminates in a horizontal line extended backward.

The inclined sides of V and W do not meet, 70 but are connected at the bottom by horizontal lines extended beyond the side lines. The left portion of W is extended below the right portion, and the inner inclined lines cross each other, and are connected at the top by a horizontal line. 75

The lower portion of Z consists of a horizontal and an inclined line extended upward and forward of the upper corner of the letter.

The top of the character & is a straight horizontal line, which is extended at an acute angle to the top line, downward obliquely to the right, across the curved body of the character. 80

The letters A E in the diphthongs AE and 85 OE are formed the same as when used separately, except that the left portion of A is extended below the bottom of the other portions of the diphthong.

In the word "The" the top line of T extends across the upper portion of the vertical line 90 of h, and terminates in an upward backward curve. The forward portion of h extends below its vertical line, and terminates in a horizontal line extended forward. The bottom line of T extends forward below the body of 95 h. e is detached, and is located between the top line of T and the bottom line of h.

The letters in the word "AND" are the same as when used in other words, or separately. A is placed so that its lower ceriph 100

(over)

intersects the middle portion of the left vertical line of N, and D is placed so that its top line extended intersects the lower portion of the right vertical line of N.

5 In the combination CH the line forming C intersects the upper portion of the left vertical line of H, and terminates at the top in a curve back of and near the top of that line, and is curved downward below that line, and 10 terminates below back of the front line of H.

In the character "Co." C encircles most of o. A curved line is extended from the top of the letter C downward and forward across the upper portion of o and terminates within the 15 letter o.

The character \$ is composed of S, formed as described and shown, and a single vertical line through the center of S.

A short curved line extends downward and 20 back ward from the top of the numeral 1. The top of 4 is scrolled backward. The bottom of 7 terminates in a forward scroll. The top of 8 is formed by a horizontal line with a downward, short, vertical terminal line. At the 25 upper right corner of this numeral the lines are not connected. The numeral 9 is formed by a continuous disconnected curved line.

What I claim as new, and desire to secure by Letters Patent, is—

The design for a font of printing-type, in which the right side line of A extends below the left line; the upper ends of the side lines are connected by a horizontal line extended beyond the side lines, and the middle lines of A and H extend across and beyond the left 35 side lines; the lower curve of B extends below and terminates in an upward curve the back of the letter; the upper portions of C, G, and S are formed by horizontal and downward and vertical lines; the base-line of E extends beyond the top line, and the base-line of E and L terminate in upward left oblique lines; the middle portions of E and F are formed by horizontal and oblique lines, these and the letters J K M N O P Q R V W Z and the other 40 portions of the design being substantially as described and shown.

In testimony whereof I affix my signature in presence of two witnesses.

WILLIAM F. CAPITAIN.
